UNITED STATES PATENT OFFICE

2,420,954

ELECTROLYTIC PRODUCTION OF SUCCINIC
ACID FROM BUTYROLACTONE

Robert M. Isham, Okmulgee, Okla., assignor to
Danciger Oil & Refineries, Inc., Fort Worth,
Tex., a corporation of Texas

Application June 12, 1941, Serial No. 397,809

1 Claim. (Cl. 204—79)

1
This invention relates to the production of di-basic acids from corresponding lactones, more particularly to the production of succinic acid from butyrolactone.

In recent years the demand for succinic acid and its derivatives has markedly increased. In addition to its employment in the medicinal field, succinic acid is of importance in synthetic resin manufacture. This acid can be reacted with glycol, for example, to produce alkyd resins. Additionally it may be utilized as a catalyst or a modifier for phenol-aldehyde condensation products. Certain of its derivatives, as for example succinic glyceride, serve as effective plasticizers for the alkyd type of resins.

The present invention relates to a simple and efficacious method of producing succinic acid from a readily available source material, namely butyrolactone, which may be extracted from pyroligneous acid residues.

It is known that among the general methods of formation, succinic acid may be produced by the oxidation of butyrolactone. In the past this has been effected by the utilization of chemical oxidizing agents, such as the chromates and permanganates. Such a method of production is quite difficult by reason of the considerable solubility of succinic acid in water. This solubility necessitates the employment of expensive extraction methods for the recovery of the succinic acid from the resulting reaction mixtures.

As a result of considerable experimentation it has been determined that butyrolactone may be converted to succinic acid electrolytically. As will be seen, such a process presents marked advantages in that it enables the continuous production of succinic acid in high yields and utilizing simplified equipment.

In order to enable a more ready comprehension of the invention there is shown in the single figure of the accompanying drawing, in diagrammatic form, a system in which it may be effectuated.

In the course of investigations from which the present invention eventuated it was ascertained that neither butyrolactone nor succinic acid is reduced by the hydrogen evolved at the cathode of an electrolytic cell where such cathode consisted of the common electrode materials, such as graphite, copper, lead and platinum. It is thus apparent that high yields of the acid are obtainable.

It was further determined that while a diaphragm cell may be used not only is this unnecessary but it is not as effective as a simple

electrolytic cell. This is due to the fact that in the diaphragm cell the anion of the electrolyte tends to become concentrated in the anode compartment. This necessitates an intermittent or continuous withdrawal of the contents of this compartment, the separation of the contained succinic acid and the return of the unoxidized butyrolactone to the cell. The preferred operation, therefore, is eminently simple and consists in utilizing a simple cell for the electrolysis of a solution of butyrolactone containing an added electrolyte to produce high yields of succinic acid. As will be seen hereinafter, the cell may be operated intermittently or continuously, the succinic acid readily separated from the solution and a substantially quantitative conversion secured.

Any suitable electrolyte may be employed and such electrolyte preferably is neutral or acid in character, such for example as sodium sulphate or sulphuric acid.

Essentially the process comprises establishing a conductive solution of butyrolactone as an anolyte and utilizing this as a depolarizer, in an electrolytic cell, to absorb and react with evolved oxygen. As will be appreciated by those skilled in the art, the amount of oxidation is a function of the concentration of the butyrolactone, its diffusion, the current density at the anode, the temperature of the electrolytic bath and the nature of the anode materials.

In the present process it is desirable to operate at quite elevated temperatures. Succinic acid displays a marked increase in solubility in water with increase in temperature. For example, at 20° C., 6.8 grams of the acid are dissolved in 100 cc. of water whereas at 100° C., 121 grams dissolve in 100 cc. of water. This rapid increase in solubility with elevated temperatures is happily utilized in the present method to separate the formed succinic acid from the liquor removed from the cell. By operating the cell at elevated temperatures and by chilling the treated liquor the succinic acid is crystallized and the crystals which form are readily separated from the liquor, as for example in a filter or preferably a continuous centrifuge. For these reasons, as noted, it is preferable to maintain the electrolyte at elevated temperatures and it is preferred to operate at about between 40° C. to 70° C. or higher.

As noted above, the conductive electrolyte which is employed is preferably neutral or acid in character. The concentration of the electrolyte in the aqueous solution may be relatively widely varied; excellent results have been obtained by employing sulphuric acid in concentrations of

from about 5 to 10% of the aqueous solution being treated.

Similarly it has been determined that the current is not critical but is susceptible of wide permissive latitude. In the preferred operations current densities of from about 2 to 3 amps. per sq. dm. and a potential drop of from 2 to 2½ volts are found to be satisfactory.

As will be appreciated, the process may be carried out in a variety of specifically different apparatus of which that shown in the drawings is illustrative. In a typical embodiment of the invention the initial charge may be made up in the mixing tank 1. Such tank is provided with any suitable stirring or agitating mechanism 2. The butyrolactone which is to be treated is fed to the tank in controlled amounts through the line 3 and the make-up water, containing the electrolyte, such as sulphuric acid, is fed through the line 4. As noted previously the amounts fed to the tank are controlled so as to insure an ultimate solution containing between about 20% and 50% of butyrolactone and from about 5% to 10% of sulphuric acid.

The mixing tank is connected to the electrolytic cell 5 by means of the line 6 which is controlled by valve 1. Preferably the line 6 discharges into a weir-box 8 from which the charging solution overflows into the cell.

Preferably, as shown, the cell is of an elongated type so as to insure the desired prolonged contact of the electrolyte with the anode to insure complete oxidation. In the preferred embodiment the bottom section 9 of the cell serves as the anode and may be constructed of lead, graphite or other conductive and acid resistant material. The elongated cell is provided with the centrally positioned elongated cathode 10 which may be constructed of copper, graphite, platinum or other suitable material. The cathode may, of course, vary widely in design and shape and may be in the form of a perforated plate, a wire mesh and the like. The cathode and anode are suitably connected in a direct current circuit as shown.

The cell is provided with the outlet or vent pipe 11 through which the hydrogen which is evolved is withdrawn. The treated solution is withdrawn from the cell through the line 12 which, as shown, is constructed so as automatically to maintain a desired liquid level in the cell 5.

The overflow pipe 12 communicates with any suitable cooling mechanism. This may be of any desired type and is shown as a tank 13 provided with the stirring mechanism 14. The tank may be provided with internal coils through which cooling medium is circulated or with an external cooling jacket or both. As explained, the treated solution is rapidly cooled in this unit so as to effect crystallization of the succinic acid produced in cell 5.

The cooling tank 13 communicates with any suitable means for separating the solid succinic acid crystals from the mother liquor. While this may be effected in any type of filtering or draining mechanism it is preferred to use accelerated filtration and for this purpose the centrifuge 16 is employed. In this unit the crystallized acid is collected in the basket of the centrifuge and the mother liquor flows through line 17, controlled by valve 18 to the receiving tank 19. In the course of the treatment the succinic acid crystals in the basket may be washed with a spray of ice water and the wash water may be discharged to

the tank 19. In the event that the quantity of wash water added exceeds that necessary to replace the water vaporized and electrolytically decomposed during electrolytic action, the excess quantity of water may be drained off through line 20, controlled by valve 21. The liquid accumulating in the liquid tank 19 which comprises an acid aqueous solution containing some small amount of succinic acid may be returned to tank

10 1 by means of the line 22 having the interposed pump 23. It is particularly to be noted at this point that in as much as the succinic acid is not reduced in the cathode it is unnecessary to remove the uncrystallized portion from the liquor in receiving tank 19 before recycling to the electrolytic cell.

It will be appreciated that with the described type of apparatus there is provided a cyclic method in which butyrolactone may continuously be 20 converted to succinic acid in substantially quantitative yields. The provision of the rapid cooling of the treated electrolyte insures a removal of succinic acid in solid phase from the mother liquor.

The efficacy of the process will be more particularly appreciated upon a consideration of a typical operation. Utilizing an apparatus of the type described and operating upon an electrolyte containing 5% of sulphuric acid by volume and 30 35% of butyrolactone by volume a quantitative conversion of the butyrolactone to succinic acid was secured, namely 118 parts by weight of succinic acid from 86 parts by weight of butyrolactone in the charge. In this operation the current density employed was 2.5 amps. per sq. dm. with a potential drop of 2.4 volts. In these circumstances the cell was operated with a current efficiency of 96%. During this operation the temperature of the electrolyte in cell 5 was maintained at 62° C. and the temperature of the liquor discharged through line 15 was 4° C. The cell employed for this operation was provided with a copper cathode and a lead anode.

The process, as indicated, is eminently simple. 45 It is found that, in operation, the evolution of hydrogen from the cathode is copious and is evolved so rapidly and continuously that it effectively agitates the solution so that no mechanical agitation is necessary. Of course, if desired, mechanical agitation may be used to supplement such gas agitation especially in certain cell designs.

It is found too that a sufficiently elevated temperature may be maintained in the cell by the 55 heat generated by the electrolysis of the solution and the heat of reaction resulting from the oxidation of the butyrolactone. Whenever desirable the desired temperature may be maintained by utilizing heating means, such as immersion heaters, closed heating coils and the like in the cell 60 5 and/or the charging tank 1.

It is found that the electrolytic oxidation described is rapid and substantially quantitative. Since neither butyrolactone nor succinic acid are 65 cathodically reduced there are no practical limitations imposed on the percentage of these in the liquor which is recycled. If for any reason it is desired to accelerate the oxidation, suitable catalysts (oxygen carriers) may be employed as addition agents, as for example cerous sulphate 70 may be employed. However, as noted, the action is so rapid and the current efficiency so high that for efficient and practical operations such addition agents are unnecessary.

It will be appreciated that the described method

is characterized as highly by its simplicity as by its effectiveness. The apparatus required is of the simplest possible form and the method is so free from critical factors as to permit continuous operation. Thus while a preferred embodiment of the invention has been described it is to be understood that this is given as illustrative of the fundamental concept of the electrolytic production of the desired acid.

I claim:

A method of producing succinic acid from butyrolactone which comprises acidifying an aqueous solution of butyrolactone with sulphuric acid, heating the solution to a temperature of between about 40° C. and 70° C., electrolyzing the solution in contact with an anode of large surface area, subsequently chilling the solution to recover therefrom crystals of succinic acid.
